UNITED STATES PATENT OFFICE

PHILIP RAY COURSEY, OF RICHMOND, ENGLAND, ASSIGNOR TO DUBILIER CONDENSER CORPORATION, OF NEW YORK, N. Y., A CORPORATION OF DELAWARE

ELECTRICAL CONDENSER

Application filed June 23, 1926, Serial No. 118,102, and in Great Britain July 3, 1925.

This invention relates to electrical condensers, and particularly to electrical condensers mounted within a suitable housing of insulation.

5 An object of the invention is to provide a condenser which is required to operate at a considerable potential, and which is so constructed that it can be well encased and properly clamped so that the parts of the condenser can be maintained in the most efficient condition.

Other objects and advantages of the invention are set forth in the following description taken with the accompanying drawings, and 15 the novel features are pointed out in the appended claims; but the description is illustrative only, and I may vary the details presented herein without departing from the principle of the invention or exceeding the 20 broad meanings of the terms in which the appended claims are expressed.

On the drawings:

Figure 1 is a longitudinal section through a condenser of my invention.

25 Figure 2 is a top view thereof; and

Figure 3 is a cross section of the line 3—3 of Figure 1.

The same numerals identify the same parts throughout.

30 The numeral 1 is utilized to indicate the body of the condenser which comprises a suitable number of metallic plates or the like, separated by insulation and encircled by a clamping ring 2. The condenser and ring are 35 disposed in a suitable housing, which is shown as having the form of an open-ended tubular body or housing 3, one end of which is closed by a bottom 4 and the other by a top 5. At 6 and 7 are terminals for the condenser which 40 may be in the form of bands, one of which is connected to the ring 2, and the other to the opposite terminal of the body of the condenser 1. This condenser may be designed as required, and it is shown as made up of a number 45 of sections 8 separated by sheets of insulation 9. Inside of the ring 2 are clamping blocks 10 which engage the opposite ends of the condenser 1 and the ring may carry a screw 11 engaging one of the blocks so that 50 when the screw is turned up, the condenser

may be put under as much compression as is desired.

One of the terminal conductors 6 is connected to a binding post 12 in the top 5 and the other terminal conductor 7 is connected to a binding post 13, also mounted in the top 5. The binding posts 12 and 13 may carry binding nuts 14 and washers 15 and be united by a strip of insulation or reinforcement 16.

The upper end of the body of the casing is 60 provided with a counter-bored shoulder 17 on which the body rests, and upon the shoulder the casing may have a projection bead or rib 18 opposite a corresponding groove 19 in the rim of the closure or top 5. The top fits 65 loosely into the adjacent end of the body of the casing and is secured by cement 20, which hardens and forms a seal and so engages the rib 18 and the groove 19 as to hold the top in place.

The bottom 4 is provided with a circular rib 21, and the lower end of the body of the casing is encircled by this rib. This rib projects inward somewhat, as indicated at 22 and the lower edge of the body of the casing is extended somewhat, as indicated at 23, so that while the lower end of the body is of less diameter than the diameter of the rib to enable the body to fit inside of the rib against the bottom 4. The insertion of cement 20 between the rib 21 and the body will act as in the case of the top 5 to secure the bottom of the casing and the body thereof tightly together, making a sealed joint; the hardened cement 20 holding the extended end of the body against withdrawal past the inward projecting edge of the rib 21.

The binding posts 12 and 13 may consist of headed screws which are passed through the top 5 with the heads inside clamping the extremities of the conductors 6 and 7. When the closure or top 5 is put on the casing, the condenser 1 and the ring 2 suspended from this top, occupy the space inside of the body of the casing 3 and this space can then be filled with wax to embed the casing 1 and clamp 2, and then the cement 20 can be used to seal the top in place. The finished condenser is thus very solid and strong in construction and the 100

parts inside of the casing are supported to the best advantage.

It is also apparent that the foregoing construction gives a uniform minimum spacing 5 between the clamp 2 and body 3 at all adjacent points or faces which reduces the possibility of breakdown of the condenser and also enables the over-all dimensions of the casing to be reduced.

10 Condensers of this construction are especially useful as anode stopping or anode feeding condensers to operate at a high voltage above the earth. They may also be employed as high-frequency by-pass condensers or as grid 15 condensers in radio transmitters.

The top 5 is preferably made of some good insulation and the body of the casing 2 should be of some good insulation, such as porcelain. Preferably the bottom 4 is of metal.

20 For large transmitters requiring large anode-feed condensers, standard metal enclosed condensers may be used in place of the condenser 1, mounted upon porcelain insulators in the casing to provide the necessary 25 insulation from earth. For very large radio transmitters the anode-feed condensers are supplied in the form of oil-filled steel tanks in which the complete condenser is supported on appropriate porcelain insulation.

30 The above described condenser is also suitable for use in low power transmitting circuits operating at 100 metres and below, for aerial series condensers, oscillation circuit condensers, grid condensers, etc.

35 The special object of this type of condenser is to meet the demand for anode feed condensers, grid condensers, etc., for low power valve transmitting purposes. For such use the condenser is called upon to carry small 40 radio frequency currents not usually exceeding one or two amperes super-imposed upon a D. C. voltage of 3000 volts. From the position of the condenser in such circuits, the whole condenser is usually operated at a 45 radio frequency potential to earth, and this construction with a porcelain case gives a very neat arrangement for this purpose, and avoids the use of any additional insulators for supporting the condenser. This model is also 50 finding favor for use in oscillation circuits of low power transmitters where it will have to carry only a few amperes of radio frequency current. It is quite useful also as an aerial series condenser for the same class of trans- 55 mitters, as for those uses also the condenser can operate at a radio frequency potential to earth without additional insulators.

Having described my invention, what I believe to be new and desire to secure and protect by Letters Patent of the United States 60 is:—

65 1. A condenser comprising a casing of insulation, a bottom for said casing, the bottom having a flange, and the lower end of said casing being encircled by said flange, the

flange projecting towards the casing and the lower end of the casing being extended to project towards the flange to enable the bottom and the body of the casing to be cemented together, the opposite end of the casing having a shoulder, a top for the casing resting upon the shoulder, said top having a groove encircling the rim thereof, the casing having a projecting rib adjacent said groove, cement filling the space between the rib and the rim of the top to secure the top in place and seal the casing, a clamped condenser in the casing, binding posts mounted on the top and conductors attached to the binding posts and to the condenser and suspending the condenser 70 in the casing.

2. A condenser comprising a casing of insulation, a bottom for said casing, the bottom having a flange, and the lower end of said casing being encircled by said flange, the 75 flange projecting towards the casing and the lower end of the casing being extended to project towards the flange to enable the bottom and the body of the casing to be cemented together, the opposite end of the casing having a shoulder, a top for the casing resting upon the shoulder, said top having a groove encircling the rim thereof, the casing having a projecting rib adjacent said groove, cement filling the space between the rib and the rim of the top to secure the top in place and seal the casing, a condenser in the casing, binding posts mounted on the top and conductors attached to the binding posts and to the condenser. 80

In testimony whereof I affix my signature.
PHILIP R. COURSEY.
